UNITED STATES PATENT OFFICE.

CABEL B. HOPKINS, OF PHILADELPHIA, PENNSYLVANIA, ASSIGNOR TO THE ENTERPRISE MANUFACTURING COMPANY OF PENNSYLVANIA, OF SAME PLACE.

DESIGN FOR A PERFORATED PLATE FOR FOOD-CUTTERS.

SPECIFICATION forming part of Design No. 31,680, dated October 17, 1899.

Application filed September 20, 1899. Serial No. 731,129. Term of patent 14 years.

To all whom it may concern:

Be it known that I, CABEL B. HOPKINS, a citizen of the United States, residing in Philadelphia, Pennsylvania, have invented and produced a certain new and original Design for a Perforated Plate for Food-Cutters, of which the following is a specification.

My design for a perforated plate for food-cutters is clearly illustrated in the accompanying drawings, in which—

Figure 1 is a face view of the plate, and Fig. 2 is a sectional view.

The essential feature of the design is the alternate spiral grooves and perforations.

15 A is the plate, having a series of grooves *a*,

spiral in form and communicating with an opening *a'* at or about the center of the plate. The plate also has a series of perforations *b*, alternating with the grooves.

I claim—

20 The design for a perforated plate of a food-cutter, as herein described and as shown in the accompanying drawings.

In testimony whereof I have signed my name to this specification in the presence of 25 two subscribing witnesses.

CABEL B. HOPKINS.

Witnesses:

WILL. A. BARR,
JOS. H. KLEIN.
